(57) **CLAIM**

The ornamental design for a carrier for extrusion and pelletizing equipment, as shown and described.

DESCRIPTION

FIG. 1 is a perspective view of a carrier for extrusion and pelletizing equipment showing my new design;

FIG. 2 is a top plan view thereof;

FIG. 3 is a bottom plan view thereof;

FIG. 4 is a rear elevational view thereof;

FIG. 5 is a front elevational view thereof;

FIG. 6 is a right elevational view thereof; and,

FIG. 7 is a left elevational view thereof.

The broken lines in the drawings are included for the purpose of illustrating portions of the carrier for extrusion and pelletizing equipment and form no part of the claimed design.
